UNITED STATES PATENT OFFICE.

CHARLES E. ANDERSON, OF CHICAGO, ILLINOIS, ASSIGNOR TO HENION & HUBBELL,
INCORPORATED, OF CHICAGO, ILLINOIS, A CORPORATION OF ILLINOIS.

HEATING-SYSTEM REGULATOR.

1,243,475.

Specification of Letters Patent. Patented Oct. 16, 1917.

Application filed May 18, 1917. Serial No. 169,578.

To all whom it may concern:

Be it known that I, CHARLES E. ANDERSON, a citizen of the United States, residing at Chicago, in the county of Cook and State 5 of Illinois, have invented a certain new and useful Improvement in Heating-System Regulators, of which the following is a specification.

This invention is a relief device for a 10 heating system, particularly vapor heating systems of very little pressure where extreme accuracy is required. The object of the invention is to provide a device which will relieve the boiler of any excess pressure 15 with great promptness without permanently removing from the boiler any material portion of the liquid. The invention consists in a device capable of carrying out the foregoing objects; which can be very easily and 20 cheaply made; which is satisfactory in operation, and is not readily liable to get out of order. More particularly, it consists in the special features and details of construction hereafter more fully set forth in the 25 specification and claims.

Referring to the drawings, in which similar numerals indicate the same parts throughout the several views,

Figure 1 is a central sectional detail view 30 through mechanism illustrating this invention in its preferred form, taken on the center line 1 of Fig. 2.

Fig. 2 is a corresponding view taken on the irregular line 2—2 of Fig. 1.

35 In carrying out this invention, an overflow chamber or tank connected to the heating system to be regulated is provided. This regulating tank may assume any suitable form, and still have certain essential parts

40 of this invention inclosed therein. In the highly developed form of the device illustrated in the drawing, this tank comprises in its outer walls an upper chamber 10, a casting of relatively large cross-section, a 45 pipe 12, of smaller cross-section screw threaded therein and closed by any suitable means, such as the closure cap 14. Water and steam from the boiler to be regulated, not shown, must be admitted to the regulating tank just referred to and carried to a 50 point near its bottom. In the particular case here illustrated, this is accomplished by providing in casting 10 an internal wall 16 forming the interior chamber 18, connected 55 to the boiler, or its equivalent (not shown)

through one or both of the ports 20, there being screw threaded into the bottom of the internal casting 16 a pipe 22 extending downward inside of pipe 12 to a point near, but above, the cap 14. This construction 60 affords an annular passageway 24 leading from the bottom of the regulating tank between pipes 12 and 22 into the upper chamber 26 of the regulating tank. In order to carry out this invention, the regulating tank 65 must also be provided with a pipe or passageway leading from a point near the bottom of the regulating tank, but above the bottom of pipe 22 to a point near the top of the upper chamber 26 of the regulating 70 tank. In the preferred form of invention, illustrated in the drawing, this is accomplished by inserting pipe 28 inside of pipe 22, passing it entirely through chamber 18 and suspending it by the screw threads 30, 75 so that its upper effective discharge port 32 is very near the top of the upper chamber 26. The effective cross-sectional area of pipe 28 should preferably be substantially equal to the effective cross-sectional 80 area of passageway 24, between pipes 22 and 28, and less than the effective cross-sectional area of the passage 24, heretofore described. The reason for this is that pipes 28 and 34 are designed to take care of the normal 85 working of the device while passage 24 is intended first to afford relief from excessive pressure and from a partial or complete accidental closure of passage 28, and second, to afford a ready return for liquid forced 90 into chambers 26 through passage 34 so it should be large enough to surely afford such relief. The proportions may, however, be varied, if desired.

Simply for clean-out purposes in constructing the device, the casting 10 is provided with an opening 36 normally closed by a screw threaded cap, not shown in the drawings.

In the extreme top of casting 10 is an escape pipe 38 hereafter referred to as a discharge port, terminating in an extremely shallow, wide, relief chamber 40 having on its top a relief outlet 42 which may, if desired, be connected to a pipe leading to a 100 chimney or the like. Inside of this relief chamber 40 and directly opposite the entrance of the pipe 38 therein is a suitably supported baffle plate 44 of any suitable design which will insure the prevention of the 105 110

direct passage of liquids and gases entering the relief chamber 40 from pipe 38 to exit 42.

In the operation of the device of this invention, assume that one or both of the openings 20 are connected to the boiler to be regulated (one opening 20 being suitably closed if only one is being used) and that the device shown in the drawing is filled with water up to a point approximating the discharge end 32 of pipe 28. When, now, 10 the pressure in the boiler to be regulated rises a little, water from the boiler is forced through port 20 in the chamber 18, thence down passage 34, thence under normal conditions up pipe 28 otherwise up this pipe and pipe 24 into upper chamber 26, and thence through passage 38 into relief chamber 40. Here the water has a chance to 15 spread out and any steam or gas carried with it has a chance to get out of the water and pass around baffle plate 44, and thence out through discharge port 42. The steam or gas goes out in bubbles, and as long as the pressure in the boiler is not excessive, 20 can continue to do so until the pressure in the boiler is relieved, when gravity will carry the water in the upper part of the system just described back into the chamber 26, thence through passages 24 and 34, back 25 to the boiler. Owing to the fact that the top of passage 28 is below the top of passage 24, a large part of the water returns through passage 24 without going into chamber 40 at all, except in the case of passage 28 being 30 stopped up as heretofore noted, whereupon the water and gases travel partially or wholly up passage 24 into chamber 26 and thence into 40 as described.

By the use of the device of this invention, 40 variations in pressure, large or small, may be taken care of in a low pressure heating system without any of the heating liquid escaping from the system, and requiring any expense of replacements.

Having thus described my invention, what I claim as new and desire to secure by Letters Patent, is:—

1. In a device of the class described, a 50 regulating tank having an entrance and a discharge port, a supplemental relief tank attached to said discharge port provided with a suitable baffle plate, and a discharge port of its own, a pipe leading from the entrance port of the regulating tank to a point 55 above the bottom of said tank, another pipe leading from a point slightly above the bottom of said first mentioned pipe, and from in close proximity thereto to a point adjacent to the discharge port of the regulating tank, for the purposes set forth.

2. In a device of the class described, a 60 regulating tank provided with entrance and discharge ports, a pipe leading from said entrance port to a point above the bottom of the tank, and another pipe inside the first

pipe leading from a point above its bottom to a point adjacent to said discharge port of the regulating tank.

3. In a device of the class described, a 70 regulating tank provided with entrance and discharge ports, a pipe leading from said entrance port to a point above the bottom of the tank, and another pipe inside the first pipe leading from a point slightly above its bottom to a point adjacent to said discharge port of the regulating tank.

4. In a device of the class described, a 75 regulating tank provided with entrance and discharge ports, a pipe leading from said entrance port to a point above the bottom of the tank, and another pipe inside the first pipe leading from a point slightly above its bottom to a point adjacent to said discharge port of the regulating tank, the area of the 80 passage between the first pipe and the tank 85 being at least equal to the area of the passage in the second pipe.

5. In a regulating system, a regulating 90 tank comprising a relatively large hollow upper portion communicating with a relatively smaller tubular lower portion, there being an entrance port provided midway of the height of the upper portion and a discharge port at the extreme top thereof, there being an interior chamber within the upper 95 portion of the tank communicating with the entrance port, a pipe communicating with said inner chamber extending down inside of but clear of the tubular passage to a point near its bottom, and a second pipe inside the first pipe extending from a point slightly above the first pipe's bottom through 100 said interior chamber and discharging into the upper portion of the device.

6. In a regulating system, a regulating 105 tank comprising a relatively large hollow upper portion communicating with a relatively smaller tubular lower portion, there being an entrance port provided midway 110 of the height of the upper portion and a discharge port at the extreme top thereof, there being an interior chamber within the upper portion of the tank communicating with the entrance port, a pipe communicating with 115 said inner chamber extending down inside of but clear of the tubular passage to a point near its bottom, and a second pipe inside the first pipe extending from a point slightly above the first pipe's bottom through 120 said interior chamber and discharging into the upper portion of the device, this in combination with a relief chamber provided with a baffle plate attached to the discharge port of the regulating tank.

7. In a device of the class described, a 125 tank adapted to contain a quantity of liquid, the same provided with a discharge port in its upper portion, a fluid conducting member open to discharge into said tank at a point adjacent to its bottom, and a pipe pro- 130

vided with an opening inside said fluid conducting member slightly above its bottom, and a discharge opening inside the tank adjacent to its discharge port.

- 5 8. A regulating device for a heating system comprising a tank made of a relatively large upper hollow member provided with a discharge port and a smaller pipe like member closed at its bottom extending some 10 distance below the upper member, a fluid conducting member extending down inside the pipe portion of the tank open to discharge into said tank at a point above the bottom of said pipe portion, and a second 15 fluid conducting member having one port

opening inside the first fluid conducting member and above the level of the latter's lower port, and its other opening entering the body of the tank at a point above the juncture of the pipe portion of the tank 20 with the upper portion of the tank for the purposes set forth.

In witness whereof, I have hereunto subscribed my name in the presence of two witnesses.

CHARLES E. ANDERSON.
